UNITED STATES PATENT OFFICE.

CURTIS HUSSEY VEEDER, OF HARTFORD, CONNECTICUT, ASSIGNOR TO THE VEEDER MANUFACTURING COMPANY, OF HARTFORD, CONNECTICUT, A CORPORATION OF CONNECTICUT.

ODOMETER.

1,000,861.

Specification of Letters Patent. Patented Aug. 15, 1911.

Application filed January 12, 1911. Serial No. 802,182.

To all whom it may concern:

Be it known that I, CURTIS HUSSEY VEEDER, a citizen of the United States, residing in the city of Hartford, in the State of Connecticut, have invented certain new and useful Improvements in Odometers, of which the following is a specification, reference being had to the accompanying drawings, forming a part hereof.

10 This invention relates to the means for actuating hub odometers for motor and other vehicles, which are mounted within casings secured to or forming parts of the hubs of vehicles and rotate therewith, the actuation 15 of the registering mechanism being effected through connections to the stationary axles upon which the wheels are mounted.

The invention is particularly concerned with the actuating connections and has for 20 its object to provide mechanism by which the register shall be driven in one direction only, while the actuating mechanism itself is reliable in operation and offers no great difficulties in manufacture.

25 The invention will be more fully explained hereinafter with reference to the accompanying drawings in which it is illustrated, and in which—

Figure 1 is a view, partly in end elevation 30 and partly in transverse section, of a wheel hub with the invention applied thereto. Fig. 2 is a view in section on the plane indicated by the line 2—2 of Fig. 1, looking in the direction of the arrows. Fig. 3 is a 35 view similar to Fig. 1 but with part of the frame of the actuating mechanism removed to show the construction more clearly. Fig. 4 is a view in section on the plane indicated by the line 4—4 of Fig. 1, looking in the 40 direction of the arrows.

In the several figures of the drawings enough of a wheel hub *a* is shown to enable the application of the invention to be understood, a portion of the stationary axle, on 45 which the wheel is mounted, being indicated at *b* in Figs. 2 and 4. The hub is shown as having formed integrally therewith a cap *c* which forms a register chamber *c'*, separated from the axle chamber *a'* by a plate *d* which 50 is removably secured in the hub and supports the driving mechanism. The register *e* is attached to the inner face of the cap *c*, which is provided with a glazed sight opening *c''* through which the register may be 55 read. The present invention is not con-

cerned with the construction of the register itself, which may be of any suitable kind, adapted to be actuated by the continuous rotation of its driving shaft *e'*. The latter has secured thereon a bevel gear *e''* which 60 meshes with a bevel gear *f* on a short shaft *f'*, mounted in bearings in the plate *d* and in the frame member *d'*. The shaft *f'* also has secured thereto a ratchet wheel *f''* which is engaged by a spring-pressed detent pawl *f'''* 65 (shown in dotted lines in Fig. 1) and by a spring-pressed driving pawl *f''''*. The latter is mounted on a carrier *g* which is pivotally mounted on the shaft *f'* and has connected thereto the link *g'* of an eccentric *h*. The 70 latter is secured to a shaft *h'* which is mounted in suitable bearings in the plate *d* and frame member *d'*, with a suitable stuffing box *d''* so as to exclude dirt and grease from the register chamber, and has secured 75 thereto a gear *h''* which meshes with a corresponding gear *h''''* secured to the end of the axle *b*.

As the gear *h''''* is held from rotation and as the gear *h''* revolves around the gear *h''''*, 80 the eccentric *h* will be rotated about its axis, whether the vehicle wheel be rotated in one direction or the other, and will actuate the driving pawl *f''''*, thereby causing a forward 85 rotation of the driving shaft *e'* of the register *e*. It will be seen not only that the mechanism is reliable but that, the gears *h''* and *h''''* having a somewhat loose engagement, the driving mechanism is not affected by relative displacement of the hub and axle 90 and furthermore, as all parts of the driving mechanism except the gear *h''''* are supported by the removable plate *d*, it is easy to assemble the mechanism.

It will be understood that various changes 95 in details of construction and arrangement may be made to suit different conditions of use and that the invention, therefore, is not restricted to the precise construction shown and described herein.

I claim as my invention:

1. The combination with an axle and a wheel hub, of a register supported by the hub, a shaft and eccentric mounted eccentrically in the hub, an eccentric link, a ratchet wheel mounted eccentrically in the hub, a pawl carrier and pawl, said pawl carrier being mounted concentrically with the ratchet wheel and connected to the link, a bevel gear mounted concentrically with the 105 110

ratchet wheel, a bevel gear meshing therewith and connected with the register, and means whereby said shaft is actuated from the axle.

- 5 2. The combination with an axle and a wheel hub, of a register supported by the hub, a shaft and eccentric mounted eccentrically in the hub, an eccentric link, a ratchet wheel mounted eccentrically in the hub, a pawl carrier and pawl, said pawl carrier being mounted concentrically with the ratchet wheel and connected to the link, a

bevel gear mounted concentrically with the ratchet wheel, a bevel gear meshing therewith and connected with the register, a gear 15 on said shaft and a gear loosely engaging therewith and secured to the axle end.

This specification signed and witnessed this 10th day of January, 1911.

CURTIS HUSSEY VEEDER.

Signed in the presence of—

CHARLES G. ALLYN,
AMASA TROWBRIDGE.
